FLUID ACTUATED MECHANISM

John M. Shimer, Dallas, Tex.

Application October 23, 1941, Serial No. 416,180

11 Claims. (Cl. 60—52)

1

This invention relates to new and useful improvements in fluid actuated mechanisms and systems.

One object of the invention is to provide an improved actuating mechanism which is particularly adapted to operate a well pump but which may be employed to operate any reciprocating member, and which utilizes a hydraulic fluid so as to eliminate the use of mechanical reciprocating means and reduce operating and maintenance costs.

An important object of the invention is to provide an improved actuating mechanism for controlling the operation of a piston by alternately supplying a predetermined volume of hydraulic fluid to the opposite sides of the piston to reciprocate the same, whereby said piston may be operated from the surface by a fixed, constant quantity of fluid without employing the usual sucker or pump rods, and whereby the stroke of the piston may be lengthened to permit a reduction in the number of strokes per volume of well fluid lifted; the fluid applied to one side of said piston being released upon the application of fluid to the other side thereof so as to permit operation of the piston by an actuating fluid of relatively low pressure.

Another object of the invention is to provide an improved actuating mechanism, of the character described, wherein the actuating fluid is supplied to the piston by surface control means which is synchronized therewith and with the surface pump, whereby the reciprocation of said piston is positively controlled at the surface.

A particular object of the invention is to provide an improved actuating mechanism for operating a well pump which includes a pump plunger of the displacement type having an actuating member connected thereto for reciprocating the same, together with a rotary control valve at the surface for delivering a predetermined quantity of actuating fluid to the member, whereby the reciprocation of the plunger is controlled directly by the rotation of the valve and whereby it is unnecessary to admix the actuating fluid with the well fluids.

A further object of the invention is to provide a mechanism, of the character described, wherein the surface control valve is so constructed that the flow of fluid to the piston may be proportioned in any desired manner, whereby the operation of a pump plunger or other member which is reciprocated by a differential piston may be readily controlled by said valve without variation in the strokes of said plunger or member.

2

Still another object of the invention is to provide an improved mechanism, of the character described, wherein the flow of the actuating fluid to the reciprocating piston is through conductors separate from the well fluid column so as to prevent mixture of said fluids, and wherein the fluid applied to and released from the surfaces of said piston flows through the surface control valve which is constantly rotating in synchronization with the reciprocation of the piston so as to effect a smooth, continuous operation of the plunger without interruption.

Another object of the invention is to provide an improved actuating system for a reciprocating mechanism which consists of supplying a predetermined constant quantity of operating fluid for each reciprocation of the mechanism and proportioning the quantity of the fluid delivered for each stroke of said mechanism, whereby a uniform continuous operation of the mechanism is had.

A further object of the invention is to provide an improved system of elevating fluids which consists of supplying a given constant volume of actuating liquid for a single cycle of accumulation and elevation of the well fluids and proportioning the delivery of the actuating fluid in accordance with the volumes required to accumulate and elevate said well fluids so as to effect a smooth, continuous elevation of the well fluids.

30 A still further object of the invention is to provide an improved rotary control valve for proportioning the flow of actuating fluid to the piston, the fluid being delivered to the valve by a surface pump of the positive displacement type and being rotated at a speed in direct relation to the speed of the pump, thereby permitting the use of a relatively inexpensive, high speed pump.

A construction designed to carry out the invention will be hereinafter described together with other features of the invention.

The invention will be more readily understood from a reading of the following specification and by reference to the accompanying drawings, as an example of the invention is shown, and wherein:

Figure 1 is a schematic plan view of an actuating mechanism, constructed in accordance with the invention, and showing the position of the valves during the downstroke of the piston plunger.

Figure 2 is a view, similar to Figure 1, showing the positions of the valves during the upstroke of said piston.

55 Figure 3 is an enlarged, longitudinal, sectional

view of the rotary valve during the downstroke of the piston.

Figure 4 is a cross-sectional view, taken on the line 4-4 of Figure 3.

Figures 5, 6, 7 and 8 are cross-sectional views taken on the lines 5-5, 6-6, 7-7 and 8-8, respectively, of Figure 3, showing the relationship of various portions of the valve element and housing during the downstroke of said piston.

Figures 9, 10, 11 and 12 are views, similar to Figures 5, 6, 7 and 8, respectively, showing the relationship of the same portions of said valve element and housing during the upstroke of the piston.

Figure 13 is a schematic plan view showing a modified form of actuating mechanism, and

Figures 14, 15, 16 and 17 are transverse, vertical, sectional views showing the positions of the valves and cams of the modified form during the downstroke of the piston, the positions during upstroke of said piston being shown in dotted lines.

In the drawings, the numeral 10 designates the usual well casing which extends substantially throughout the entire length of the well bore and which has its lower end open so that the well fluids may enter the casing and flow upwardly therein. A well tubing 11 depends axially within the well casing, being suspended from a well head 12 mounted on the upper end of said casing and being packed-off from the head by suitable packing 12'. The lower end of the tubing terminates at a point above the lower end of the casing and has the conventional perforated pipe 13 secured thereto. For controlling the flow of the well fluid from the perforated pipe 13 to the tubing, a standing valve 14 is interposed between said pipe and tubing. Immediately above the standing valve, a suitable packer 15 surrounds the tubing and engages the wall of the well casing so as to pack off the annular space between said tubing and casing. A displacement chamber 16, which has its upper end communicating with the annular space between the casing and tubing by an upwardly-opening check or discharge valve 17 disposed within said space and its lower end in communication with the pipe 13, is provided at the lower end of the tubing.

A cylindrical sleeve 18, of a greater diameter than the tubing, is connected in said tubing and is spaced above the displacement chamber by an inter-connecting section of tubing 24. Disposed within the sleeve 18 is a cylinder 19 which extends axially substantially throughout the length of said sleeve and which is of a smaller diameter than said sleeve to provide an annular space 20 therebetween. Communication between the lower end of the cylinder 19 and the space 20 is established by a plurality of ports 21 formed in the lower end of said cylinder. A piston 22, having an elongate plunger 23 depending axially therefrom, is mounted to reciprocate within the cylinder 19 and is adapted to be actuated by hydraulic fluid admitted alternately to the upper and lower ends of said cylinder. The plunger 23, which is of substantially the same diameter as the internal diameter of the tubing 24 so as to have a snug sliding fit or engagement therein, is of sufficient length to extend into the chamber 16 when the piston 22 is within the lower portion of the cylinder 19. Since the plunger is solid in cross-section, downward movement of the same through the chamber will force the well fluid admitted thereto by the standing valve 14 out through the check valve 17 into the annular space

between the tubing and casing. The diameter of the plunger is substantially equal to the internal diameter of the tubing section 24 which connects the displacement chamber and the sleeve 18 so as to have a sliding fit therein, this sliding fit or engagement serving as a seal between said chamber and sleeve to prevent the passage of fluid from one to the other. For admitting a hydraulic fluid to the upper end of the cylinder 19, a macaroni string 25 extends axially through the tubing 11 and is secured to and packed off from the upper extremity thereof by suitable means 25'. Due to the provision of the depending plunger 23, it is obvious that the lower surface of the piston 22 is of less cross-sectional area than the upper surface thereof, whereby a greater volume of fluid is required to move said piston downwardly a given distance than to raise the piston the same distance.

For controlling the flow of fluid to the tubing 11 and macaroni string 25, a rotary control valve 26 is provided at the surface and consists of a cylindrical, horizontally-disposed housing 27 having a tubular valve element 28 rotatably mounted therein, as will be hereinafter more fully described. Communication between the tubing and the valve 26 is established by a suitable conduit 29, while a pipe 30 connects said valve to the macaroni string. One end of the valve element 28 projects beyond the valve housing 27 and has a sprocket 31 mounted thereon, whereby said element may be positively rotated in a clockwise direction (Figures 4 to 12) by the shaft 32 and sprocket 33 of a suitable pump 34, the sprocket 33 being connected to the sprocket 31 by a continuous chain 35. The pump 34, which is preferably of the positive displacement type and which may be a comparatively inexpensive, high-speed pump, is driven by the engine 36 through the sprockets 37 and 38 and continuous chain 39.

The operating or actuating fluid is conducted from a suitable storage tank 40 to the valve 26 by the pump 34 through a suction line 41, conduit 41 and Y 42, whereas the fluid is discharged from said valve to the tank through a return pipe 43. As is clearly shown in Figure 3, the branches of the Y 42 are screw-threaded into spaced radial ports 44 and 45 formed in the valve housing 27 and disposed within the same horizontal plane. A pair of similar, horizontally-aligned ports 46 and 47 are disposed between the ports 44 and 45 for receiving the pipe 43 and its branch 48, the plane of the latter ports being diametrically-opposed to the plane of the former ports. The ports 44, 45, 46 and 47 communicate with arcuate or semi-circular recesses 64, 65, 66 and 67, respectively, which are formed in the bore 49 of the valve housing. The recesses 64 and 66 are of the same circumferential length and are disposed within diametrically-opposed planes, while the circumferential length of the recess 65 is equal to the circumferential length of the recess 67 and said recesses are also disposed within planes diametric to each other.

Each end of the horizontally-disposed valve housing 27 is enlarged to provide an external, radially-extending flange 50 which is provided with a radial port 51 for receiving the conductor 29 and pipe 30, respectively. As is clearly shown in Figure 4, each port 51 communicates with an annular groove or channel 52 formed within the bore 49 of the valve housing. The tubular valve element 28 is disposed within the bore 49 of the valve housing and has an external diameter substantially equal to the diameter of said bore,

whereby the exterior of said valve element snugly engages the wall of said bore. Each end of the element is reduced in diameter and is journaled within a suitable bearing 53 mounted within a cap or closure member 54 which is fastened to the outer face of the flange 50 by bolts 55, whereby said element is supported by the bearings so as to prevent undue wear of the contacting surfaces of said element and the bore 49. As has been explained, the forward reduced end of the element 28 projects beyond the forward end of the valve housing and has the sprocket 31 splined upon its outer extremity as shown at 56. For packing off around this projecting portion of the valve element, a stuffing box 57 is preferably made integral with the forward closure member 54 and includes the usual packing element 58 and gland 59, which is adjusted by bolts as shown.

The valve element 28 is provided with an axial bore 60 which is closed at each end by suitable end members or plates 61 and which is divided by a transverse partition 62 into two cylindrical, axially-aligned chambers A and B. Communication between the chamber A and recess 65 is established by a pair of horizontally-aligned orifices 85 which extend through the wall of the valve element. A similar pair of orifices 86, which are disposed in the same horizontal plane as the orifices 85, establish communication between the recess 66 and chamber A as shown in Figures 3, 7 and 8. The recesses 64 and 67 communicate with the chamber B through identical orifices 84 and 87, respectively, the orifices being disposed within the same horizontal plane which is diametrically-opposed to the horizontal plane of the orifices 85 and 86 (Figures 5 and 6). Although the orifices 85 and 86 are disposed within the same horizontal plane, the latter orifices are out of registration with the recess 66 during the time the former orifices are in communication with the recess 65. Conversely, the orifices 86 are in communication with their recess 66 at the time the orifices 85 are out of registration with their recess 65. This is also true of the orifices 84 and 87 because their respective recesses are also disposed within diametric planes. Due to their respective size and relationship, the orifices 85 communicate with the recess 65 simultaneously with the registration of the orifices 87 with the recess 67. During this time, the orifices 84 and 86 are out of communication with their respective recesses 64 and 66 (Figures 5 to 8). However, during the time that the orifices 84 and 86 register with their recesses, the orifices 85 and 87 are out of communication with their recesses, as is clearly shown in Figures 9 to 12. The orifices 84, 85, 86 and 87 are spaced longitudinally of each other so as to prevent fluid from leaking from one pair of orifices to another, the metal-to-metal seal provided by the snug engagement between the housing bore 49 and the valve element assuring non-leakage.

The annular grooves 52 of the valve housing and bore 49 constantly communicate with the chambers A and B by means of openings 63 formed in the valve element 28 and continuously registering with said grooves. Due to the constant registration of each opening 63 with its groove 52, the conductor 29, which is screw-threaded into the rear port 51, is in constant communication with the chamber B, and the chamber A communicates at all times with the pipe 30 which is secured within the forward port 51, whereby the tubing 11 and macaroni string 25 are in con-

stant communication with said chambers B and A, respectively.

From the foregoing, it is obvious that the chamber A serves to establish communication between the ports 45 and 51 by means of the forward groove 52, opening 63, orifices 85 and recess 65, while the chamber B likewise functions to connect the port 47 to the rear port 51 through the recess 67, orifices 87, rear opening 63 and rear groove 52 when the valve element is in the position shown in Figures 1 and 3. In this position of the element 28, the pipe 30 will communicate with the Y 42 of the conduit 41 and the conductor 29 will be, in effect, connected to the branch 48 of the return pipe 43 (Figures 4, 6 and 8), whereby the operating fluid may flow from the pump 34 through the valve to the macaroni string 25 into the upper end of the cylinder 19 so as to force the piston 22 and its plunger 23 downwardly, and the spent operating fluid within said cylinder below said piston may escape through the ports 21 into the annular flow space 20 so as to displace the fluid therein upwardly through the tubing 11, conductor 29, then through said valve, branch 48 and return pipe 43 into the storage tank 40.

When the valve element rotates to the position shown in Figures 2 and 9 to 12, the pipe 30 will be connected to the return pipe 43 due to the communication between the chamber A and recess 66 by means of the registration of the orifices 86 with said recess. At the same time, the orifices 84 will be in registration with the recess 64 so as to establish communication between the conductor 29 and the Y 42 of the conduit 41 through the chamber B. With the valve in this position, the operating fluid delivered to the Y 42 by the pump 34 will be directed by the chamber B, conductor 29, tubing 11 and annular space 20 into the lower end of the cylinder 19 through the port 21 so as to exert its force against the lower end of the piston 22 and lift the same with its plunger 23. Since the pipe 30 is connected to the return pipe 43, the spent fluid within the cylinder 45 above the piston and within the tubing string 25 will be displaced through the chamber A and said pipes 30 and 43 into the storage tank 40.

Upon complete revolution of the valve element 28, the operation will be repeated with the fluid 50 from the pump 34 again being directed through the Y 42, chamber A, pipe 30 and macaroni string 25 into the cylinder 19 so as to again force the piston and its plunger downwardly. It is manifest that upon the downstroke of the piston and plunger, the standing valve 14 will be closed and the well fluids within the displacement chamber 16 will be forced through the check valve 17 into the annular space between the tubing and casing. Of course, the standing valve 14 will be open to admit the well fluids to the chamber and the check valve 17 will be closed to prevent the flow of said fluids from the casing upon the upstroke of the piston and its plunger.

As has been hereinbefore explained, the plunger 23, which depends from the piston 22 and extends through the intermediate tubing section 24 into the chamber 16, reduces the effective cross-sectional area of the underside of said piston, whereby the upper surface of the piston is of a greater cross-sectional area than the underside thereof, with the result that a greater volume of operating fluid is required to lower said piston than to lift the same an equal distance. Since there is a positive differential in the volume of operating fluid required for the upstroke and down-

stroke of the piston 22, it is necessary that the control valve be so constructed that the proper volume will be delivered to each surface of said piston. Although the differential in cross-sectional areas is determined by the cross-sectional area of the plunger 23; for the purposes of illustration, it will be assumed that the upstroke of said piston will require two gallons of fluid and that three gallons will be required for an equal downstroke thereof, or a total of five gallons per complete reciprocation. Since the valve element makes one complete revolution for each reciprocation of the piston, said element must proportion the five gallons of operating fluid delivered to the conductor 28 and pipe 30 during each revolution, three gallons being delivered to the latter and two gallons to the former. Of course, the speed of the positive displacement pump 34 must be regulated so as to deliver five gallons of operating fluid at a constant rate to the valve 26 for each revolution of its element 27 and for each reciprocation of the piston 22.

Due to the fact that the admission of the operating fluid to the chambers A and B is controlled by the co-action of the recess 65 and orifices 85 and the co-action of the recess 64 and orifices 84, respectively, said recess 65 and orifices 85 must be in registration for a sufficient duration of time to accommodate three gallons of the fluid, whereas two gallons of said fluid must be accommodated during the registration of said recess 64 and orifices 84. Therefore, the recess 65 is of a greater circumferential length than the recess 64, the ratio being three to two in accordance with the volumes required by the differential piston. Thus, the orifices 85 will be in registration with the recess 65 during approximately three-fifths or 216 degrees of each revolution of the valve element as shown by the angle X—X in Figure 8, while the orifices 84 will register with the recess 64 for approximately two-fifths or 144 degrees of each revolution, as shown by the angle Z—Z in Figure 9. During the angle of rotation X—X, the orifices 84 are out of registration with the recess 64, as shown in Figure 5, and the orifices 85 are out of registration with the recess 65 throughout the angle of rotation Z—Z, as shown in Figure 12. Since the recess 66 and the orifices 86 control the discharge of fluid from the chamber A into the return pipe 43 and are in communication simultaneously with registration of the orifices 84 and recess 64, said recess 66 is of the same circumferential length as the said recess 64, so as to permit a flow of fluid from said chamber A throughout the angle of rotation Z—Z (Figure 11). As shown in Figure 7, the orifices 86 are out of registration with the recess 66 throughout the angle of rotation X—X. The recess 67 is of substantially the same length as the recess 66 and is in registration with the orifices 87 throughout the angle of rotation X—X (Figure 6) to discharge fluid from the chamber B to the branch 48 of the pipe 43. Obviously, communication between the recess 67 and orifices 87 is shut off during the angle of rotation Z—Z (Figure 10).

As shown in Figures 5 to 8, the orifices 85 and 87 will be in registration with their respective recesses and the orifices 84 and 86 will be out of registration with their respective recesses during the angle of rotation X—X or substantially three-fifths of each revolution of the valve element. However, the orifices 84 and 86 will be in registration and the orifices 85 and 87 out of registration during two-fifths, angle of rotation Z—Z, of each

revolution of the valve element as shown in Figures 9 to 12.

As has been explained, the valve element is rotated by the pump 34 through the sprockets 31 and 33, chain 35 and shaft 32, with the rate of speed of said element being controlled by the rate of speed of the pump through the ratio of said sprockets. This ratio, of course, is determined by the volume of fluid delivered per minute by the positive displacement pump and the volume of fluid required to reciprocate the piston 22. If five gallons of fluid are required for one reciprocation of the piston, as assumed, and it is desired to reciprocate said piston twelve times per minute, the speed of the pump must be regulated to deliver sixty gallons per minute. In the event, it is desired to increase or decrease the number of reciprocations per minute of the piston, it will only be necessary to increase or decrease the speed of the pump, because the revolutions per minute of the valve element and the number of reciprocations per minute of said piston is always the quotient of the capacity per minute of the pump divided by the volume of fluid required to reciprocate the piston one time. Due to the fact that the pump 34 is of the positive displacement type, the capacity per revolution of said pump is substantially constant at all speeds within its range of operation. Since the rotation of the valve element directly controls the reciprocation of the piston, it is necessary to positively relate the speed of said element to the speed of the pump.

In operation of the mechanism, and carrying out of the method, the actuating fluid is delivered by the pump 34 from the tank 40 through the conduit 41 and Y 42 to the ports 44 and 45 and recesses 64 and 65 of the valve housing 27. With the valve element in the position shown in Figures 1, 3 and 5 to 8, the orifices 85 will be in registration with the recess 65 so that the fluid will flow through the chamber A, forward opening 63, forward groove 52, forward port 51, pipe 30, and macaroni string 25 into the upper end of the cylinder 19, whereby the force of said fluid will be exerted against the upper surface of the piston 22 so as to force the same, together with its plunger 23, downwardly. The downwardly moving plunger will displace the well fluids within the chamber 16 into the annular space of the casing 10, as has been hereinbefore explained. Simultaneously with the downward movement of the piston, the spent fluid within the cylinder 19 below said piston will be displaced outwardly through the ports 21 into the annular space 20 and then upwardly through the tubing 11 and conductor 28, through the rear port 51, rear groove 52, rear opening 53, chamber B, and orifices 87, which are in registration with the recess 67, into the port 47, branch 48 of the return pipe 43 and finally into the storage tank 40. Continued rotation of the valve element to the position shown in Figures 2 and 9 to 12, will move the orifices 84 into registration with the recess 64 and the orifices 86 into communication with the recess 66. The fluid delivered by the pump will then flow through the chamber B, rear opening 53, rear groove 52, rear port 51, pipe 28 and tubing 11 into the annular space 20 and then through the ports 21 into the lower portion of the cylinder 19 so as to lift or raise the piston 22. The upward movement of the piston will lift the plunger so as to draw fluid into the chamber 16 through the standing valve 14, as has been hereinbefore described. The upstroke of the piston

will, of course, force the spent fluid within the cylinder thereabove upwardly through the macaroni string 25, pipe 30, into the chamber A of the valve element, by means of the forward port 51, forward groove 52, and forward opening 63. From the chamber A, the fluid will be displaced through the orifices 66, recess 68, and port 46 into the return pipe 43 so as to be returned to the storage tank 40. Further rotation of the valve element merely repeats the above described 10 operation.

In commencing the operation of the herein-before described mechanism, it may happen that the piston will be at the end of its downstroke or upstroke and the valve element will be in a position to admit a full volume of fluid to the upper or lower end of the cylinder, with the result that there would be no place for said fluid. In order to prevent damage to the mechanism in this event, a by-pass line 68 extends from the conduit 41 to the pipe 43 and has a pressure relief valve 69 connected therein, whereby the excess fluid may escape or bleed through the line 68 and its valve 69 to the pipe 43 and be returned to the storage tank 40. Thus, the valve 69 serves to permit the escape of any excess liquid during the operation of the pumping mechanism. After the beginning stroke, it is manifest that the rotation of the valve element will become automatically synchronized with the reciprocation of the piston so as to actuate the same in the usual manner.

From the foregoing, it is obvious that the reciprocation of the piston 22 is positively and directly controlled by the surface valve 26 with its valve element making one revolution for each reciprocation or complete stroke of said piston. Due to the use of this valve, it is possible to actuate a differential piston in a continuous, uniform manner with a fixed volume of fluid, such as is supplied by the positive displacement pump 34. Although the mechanism has been described in connection with the operation of a displacement plunger type pump, it is to be understood that the invention is not to be limited to the operation of a pump because the mechanism may be employed to control the actuation of any reciprocating member. Attention is again directed to the fact that the speed of the valve element is directly related to the speed of the surface pump, the speed of said element being determined by the capacity per minute of the pump and the volume of fluid displaced by the piston 22 which is the volume required to complete one reciprocation thereof, and is always the quotient of said pump capacity divided by the volume displaced during one reciprocation of said piston. This valve also permits the use of relatively inexpensive positive displacement pumps which are generally high-speed pumps. Due to the provision of the macaroni string 25, a closed operating system is had so as to eliminate the objection of admixing the actuating fluid with the well fluid, thereby permitting the use of glycerin, water, or other suitable fluid as the actuating fluid. As has been explained, the rotary control valve reverses and proportions the flow of the actuating fluid so as to reverse the direction of movement of the piston and its plunger, whereby the length of stroke of said piston and plunger in each direction is controlled at the surface. The novel construction of this valve permits the same to control the flow of fluid both to and from the piston, whereby there is no sticking of the piston due to equalization of pressures. 70

The disposition of the openings of the rotary valve element and the snug engagement between said element and the bore 49 of the valve housing assures a positive seal between said openings so as to prevent the leakage of fluid from one opening to another. It is also pointed out that the valve element is supported by the bearings 53 and not by the valve housing bore, whereby frictional wear of said element and housing bore is reduced to a minimum.

It is pointed out that the reciprocation of the piston 22 may be controlled by a multiplicity of mechanisms and that it is not essential to the method to employ the valve 26 with its rotary valve element 28 for such purpose. Another form of control mechanism for carrying out the method is shown in Figures 13 to 17 and includes a horizontally-disposed shaft 70 which has a sprocket 71, similar to the sprocket 31 of the valve element 28, splined on one end thereof, whereby it may be positively rotated in a clockwise direction by the pump 34 through the shaft 32, sprocket 33, and continuous chain 35 in exactly the same manner as said valve element. A plurality of circular cams 74, 75, 76 and 77 are mounted on the shaft 70 in spaced relationship, so as to be rotated therewith for actuating valves 94, 95, 96 and 97, which are preferably of the poppet type. The cams are of the usual construction and each cam has an arcuate or semi-circular lobe made integral with the periphery thereof, as illustrated at 104, 105, 106 and 107 in Figures 14 to 17. The cam 74 and its lobe 104 are identical to the cam 76 and its lobe 106, 25 while the cam 77 with its lobe 107 is identical to the cam 75 with its lobe 105. The lobes 104 and 106 are in horizontal alignment and are disposed in a plane diametrically-opposed to the plane of the lobes 105 and 107 which are horizontally aligned. The circumferential length of the lobes 105 and 107 is greater than the circumferential length of the lobes 104 and 106, whereby said lobes 105 and 107 are comparable to the recesses 65 and 67 of the first form and 30 said lobes 104 and 106 are the equivalent of the recesses 64 and 66.

The valves 94, 95, 96 and 97 are of identical construction and each includes the usual housing or casing 78 which has its interior divided into an inlet chamber 79, and an outlet chamber 80 by a transverse, horizontal partition 81. Communication between the inlet chamber 79 and outlet chamber 80 is established by a central circular opening 82 which has its lower portion beveled to provide a valve seat 83. A valve head or disk 88, having its periphery beveled so as to engage the seat 83, is movable vertically within the chamber 79 and has a stem or rod 89 secured to the upper surface thereof. The valve stem 89 extends upwardly through the chamber 80 and is slidable through the bore of an annular collar or boss 90 which depends into said chamber from the top of the casing 78 for guiding the movement of said stem and the valve head 88. 35 For holding the head 88 in engagement with the seat 83, a coiled or helical spring 91 is confined upon the outer extremity of the stem 89 between the top of the valve casing and a disk or plate 92 carried by said stem.

The inlet chamber 79 of the valve 94 communicates with the Y 42 of the conduit 41, while the conductor 29 is connected in the outlet chamber 80 of said valve to establish communication between said chamber and the tubing 11 (Figure 14), whereby the valve serves to control the flow

of operating fluid from the pump 34 to the lower end of the cylinder 18 in substantially the same manner as the orifices 84 of the rotatable valve element 28. As shown in Figure 17, the inlet and outlet chambers of the valve 95 establish communication between one end of the branch 42 of the conduit 41 and the pipe 30 which is connected to the macaroni string 25, with the result that the flow of operating fluid from the pump 34 to the upper end of the cylinder 18 is controlled by said valve. A branch 73 is connected to the pipe 30 for conducting the spent fluid from the upper end of the cylinder upon the upstroke of the piston 22 and has its free end communicating with the return pipe 43 through the inlet and outlet chambers of the valve 96 (Figure 16). During the downstroke of the piston, the spent fluid within the cylinder below the piston is conveyed from the conductor 28 through a connected branch 72 through the chambers of the valve 97 to the branch 48 of the return pipe 43 as shown in Figure 15. Thus, the valves 95, 96 and 97 serve the same purpose and accomplish the identical results as the orifices 85, 86 and 87, respectively, of the valve element 28.

For controlling the movement of the valve head 88, a rocker arm or lever 100 is pivotally mounted above each valve on an upstanding bracket or standard 98 which is preferably made integral with the upper portion of the valve casing 78. One end of the rocker arm engages the upper end of the valve stem 89, while the other end of said arm carries a roller or wheel 100 for engaging the periphery of the respective cam of the valve. Due to the provision of the spring 91, each valve stem 89 is constantly urged upwardly into engagement with its rocker arm so that the roller of said arm will be in constant engagement with and ride upon the peripheral surface of its cam. Since the cams are constantly rotated by the shaft 70, the lobes of said cams will swing the rocker arms about their pivots to depress the valve stems 89 and move the valve heads 88 downwardly away from their seats 93, thereby permitting a flow of fluid through the valves as shown in Figures 15 and 17. When the lobes move from beneath the rollers of the rocker arms (Figs. 14 and 16), the springs 91 will exert their force to raise the valve stems and again move the valve heads into engagement with their seats. Thus, the springs serve to maintain the valves in their closed position, while the lobes of the cams open said valves. Also, the pressure of the fluid within the chambers 78 exerted against the lower surfaces of the valve heads will tend to assist the springs in holding the valves closed.

With the shaft 70 and cams in the position shown in Figures 14 to 17, the valves 94 and 96 will be closed and the valves 95 and 97 open, thereby permitting a flow of operating fluid from the pump 34 to the pipe 30, macaroni string 25, and the upper end of the cylinder 18 so as to force the piston 22 downwardly. At the same time, the fluid within the cylinder below the piston and within the space 28, tubing 11 and conductor 28 will be permitted to escape through the branch 72 and valve 97 into the branch 48 of the return pipe 43. Upon rotation of the cams in a clockwise direction to the position shown in dotted lines, the valves 95 and 97 will be closed and the valves 94 and 96 open as shown by the dotted lines in Figures 14-17. The opening of these valves will establish communication between the Y 42 of the conduit 41 and the conductor 28 and

between the branch 73 of the pipe 30 and the return pipe 43 as shown by the dotted arrows in Figure 13, whereby the operating fluid delivered by the pump will be conveyed to the lower end of the cylinder 18 so as to raise the piston and the spent fluid above said piston may be discharged through the valve 96 into said return pipe.

It is readily apparent that the valves 95 and 97 commence opening when the point D of the cams 75 and 77 engage the rollers of the respective rocker arms of said valves and the valves 94 and 96 are fully closed at this point. The valves 94 and 96 remain closed until the point C of each cam engages and passes beyond each roller. At this point, the lobes 104 and 106 of the cams 74 and 76 will engage the rocker arm rollers of the valves 94 and 96 so as to commence opening said valves. These valves will remain open and the valves 95 and 97 will remain closed until the point D again passes beneath the roller. Thus, during the angle of rotation, C-D, the valves 94 and 96 will be open and the valves 95 and 97 will be closed. However, the valves 94 and 96 will be closed and the valves 95 and 97 open during the angle of rotation D-C.

Due to the fact that it has been assumed that three gallons of operating fluid are required to lower the piston 22, and two gallons for lifting the same, the peripheral surfaces of the lobes 104 and 106 of the cams 75 and 77, which actuate the valves 95 and 97 to control the flow of fluid during the downstroke of the piston, engage their respective rocker arm rollers during approximately three-fifths or 216 degrees of each revolution of the shaft 70. The peripheral surfaces of the lobes 104 and 106 of the cams 74 and 76 engage their respective rocker arm rollers during approximately two-fifths or 144 degrees of each revolution of said shaft to hold the valves 94 and 96 open so as to control the flow of fluid during the upstroke of said piston. Therefore, it is obvious that the angle of rotation C-D and D-C are comparable to the angles of clockwise rotation X-X and Z-Z, respectively, of the rotary valve element 28. In order to prevent the flow of fluid to the valve 94 during the downstroke of the piston and to the valve 95 upon the upstroke of said piston, suitable check valves 101 are mounted in the conductor 28 and pipe 30 adjacent said valves. Similar check valves 102 are connected in the return pipe 43 and its branch 48 adjacent the valves 96 and 97 for preventing the flow of fluid from said pipe and its branch to said valve. It is readily apparent that this modified form of actuating mechanism will control the operation of a differential piston in exactly the same manner as the first form of the invention which includes the rotary valve element.

The foregoing description of the invention is explanatory thereof and various changes in the size, shape and materials, as well as in the details of the illustrated construction, may be made, within the scope of the appended claims, without departing from the spirit of the invention.

What I claim and desire to secure by Letters Patent is:

1. In a reciprocating apparatus, a mechanism including, a cylinder, a fluid-responsive member movable in the cylinder, means for conducting a hydraulic fluid to said cylinder for reciprocating the member, the surfaces of said member exposed to the fluid being of unequal cross-sectional areas so as to require unequal volumes of said fluid for

13

the strokes of the member, means for controlling the flow of the fluid to the cylinder so as to proportion the same in accordance with the areas of said member, and means for actuating and supplying hydraulic fluid to the control means.

2. A mechanism as set forth in claim 1 wherein the control means includes constantly rotating means driven by the actuating and supplying means and synchronized with the reciprocation of the fluid-responsive member.

3. A mechanism as set forth in claim 1 wherein the control means includes a constantly rotating valve element driven by the actuating and supplying means and synchronized with the reciprocation of the fluid-responsive member.

4. A mechanism as set forth in claim 1 wherein the control means includes valves and constantly rotating cam means synchronized with the reciprocation of the fluid-responsive member and driven by the actuating and supplying means for actuating the valves.

5. An actuating mechanism for a reciprocating element including, a cylinder, a piston arranged to reciprocate within the cylinder, means for conducting a hydraulic fluid to and from said cylinder for reciprocating the piston, one surface of said piston being of a greater cross-sectional area than the other surface thereof so that one stroke of the piston requires a greater volume of fluid than the other stroke thereof, a pump for supplying a fixed volume of fluid to the conducting means, and valve means interposed between the pump and conducting means for controlling the volume of fluid supplied to said conducting means, the valve means including constantly rotating means driven by said pump for proportioning the volume of fluid supplied to the conducting means in accordance with the areas of the piston surfaces for controlling the reciprocation of said piston.

6. An actuating mechanism as set forth in claim 5 wherein the constantly rotating means consists of a rotary valve element for simultaneously controlling the flow of the fluid to and from the cylinder.

7. An actuating mechanism as set forth in claim 5 wherein the valve means includes valves for simultaneously controlling the flow of the

14

fluid to and from the cylinder, the constantly rotating means consisting of cam means for actuating the valves.

8. An actuating mechanism for a reciprocating element including, a cylinder, a piston arranged to reciprocate within the cylinder, means for conducting a hydraulic fluid to the lower end of said cylinder to raise the piston, additional means for conducting the fluid to the upper end of the cylinder to lower said piston, one surface of the piston being of a greater cross-sectional area than the other surface thereof so that one stroke of said piston requires a greater volume of fluid than the other stroke thereof, valve means communicating with the conducting means for controlling the flow of the fluid thereto, the valve means including constantly rotating means synchronized with the reciprocation of the piston for proportioning the volume of fluid admitted to each conducting means in accordance with the areas of the piston surfaces so as to positively control the reciprocation of said piston, and a pump for supplying a fixed volume of fluid to said valve means and for driving the constantly rotating means.

10 9. An actuating mechanism as set forth in claim 8 wherein the constantly rotating means consists of a rotary valve element.

10 10. An actuating mechanism as set forth in claim 8 wherein the valve means includes valves, the constantly rotating means consisting of cam means for actuating the valves.

15 11. A system of the character described including, a reciprocating member having opposite actuating surfaces of unequal areas, a fluid circulating conduit having connection with the member, a source of fluid supply connected in the conduit, a pump connected in said conduit between the supply source and said member, and means actuated by the pump for controlling the flow of fluid to and from the opposite surfaces of the member in proportion to the areas thereof, the control means including constantly rotating means driven by said pump and synchronized with the reciprocation of said member for proportioning the flow of fluid in accordance with the areas of said opposite member surfaces.

JOHN M. SHIMER.
